UNITED STATES PATENT OFFICE.

THOMAS MIDGLEY, JR., OF LANCASTER, OHIO, ASSIGNOR, BY MESNE ASSIGNMENTS,
TO DELCO-LIGHT COMPANY, OF DAYTON, OHIO, A CORPORATION OF DELAWARE.

HYDROMETER.

1,412,884.

Specification of Letters Patent. Patented Apr. 18, 1922.

Application filed January 10, 1916. Serial No. 71,171.

To all whom it may concern:

Be it known that I, THOMAS MIDGLEY, Jr., a citizen of the United States, residing at Lancaster, in the county of Fairfield and 5 State of Ohio, have invented certain new and useful Improvements in Hydrometers, of which the following is a specification.

This invention relates to hydrometers and is intended to be of such construction as to 10 particularly adapt itself for use by motorists and the like.

The essential object of my invention is in 15 the construction of a hydrometer which may be easily and conveniently carried either upon the person of the motorist or in the vehicle where it will be of ready access in case it is desired to determine the density of a new purchase of gasoline. As is well known, there are various grades of gasoline now on 20 sale and it is oftentimes desirable that the motorist shall determine to his own satisfaction that he is purchasing goods as they are represented to be.

These objects I accomplish with the structure shown in the accompanying sheet of drawings, in which similar characters of reference designate corresponding parts, and in which:

Figure 1 is a general face view of my improved type of hydrometer, and,

Figure 2 shows an application of my invention.

In these drawings, there are shown a plurality of indicator elements 1, preferably in 35 the shape of beads and all mounted upon a cord or other flexible member 2. These beads are all preferably evenly spaced on the cord and are themselves of different densities. In fact, their constituency is such that 40 the one designated 3, for instance, is of a weight such that when its weight is combined with the weight of all the lower elements plus the cord weight in a given liquid, it will indicate a density of 63. By this I 45 mean that the weights of the beads below the one which floats must be taken into consideration. It is evident from this that no one bead above the lowest one on the cord, will, if acting alone, give a correct indication of 50 the density, but that its action and those of all the lower beads are mutually dependent upon one another. With my invention, the motorist may readily determine the density of the gasoline he is purchasing if this

density is measured by the last bead which 55 floats and is next to the last bead which sinks in the gasoline in which it is placed. Thus, if the beads designated 60 to 68, inclusive, float while beads 57, 58, 59 sink the density would be 60. On the other hand, if, as illustrated in Fig. 2, the beads 63 to 68 float, while the others sink, the density of this quantity of gasoline will be 63.

In the above description, it will be understood that the bead which indicates the correct density is the bead which floats just above the first submerged bead.

While, as has been explained, certain beads indicate the density of the liquid, it will be understood that the numerals applied to the successive beads as shown in Figs. 1 and 2, are those of the Baumé scale. As is well known, this scale, which is an arbitrary one, is the hydrometric scale in common use in the oil industry. To determine 75 the true specific gravity of the liquid tested it is, of course, necessary to refer to a conversion table, though for ordinary purposes the motorist is interested only in the density as given on the arbitrary scale to which 80 he is accustomed. The numerals applied to the beads in the drawings are used merely for illustrative purposes, and it will be understood that the beads may be graduated according to any arbitrary scale other than 85 the one mentioned, or to indicate specific gravities directly.

From the foregoing, it will be apparent that I have provided a type of hydrometer which may be cheaply manufactured and 90 which may be further easily transported, in that it may be conveniently placed in any of the pockets of the operator, or may be placed in any desirable locality in the vehicle itself. Further, a great amount of care 95 is not necessary in its handling, since there are no parts to break.

The hydrometer herein shown and described may be termed a full-floating hydrometer, by which I mean a hydrometer 100 that is normally freely floating at all points and is not dependent for its indications upon any particular relation of the liquid-containing vessel to the hydrometer, or upon any particular depth of liquid, the only requirement being that the liquid being measured be of sufficient depth to permit the hydrometer to float freely without having its sub-

merged parts supported in any way by the liquid-containing vessel.

While I have described and shown a preferred form of one embodiment of my present invention, it will be understood that detailed changes in structure and location may be made without departing from the spirit and scope of the present invention.

What I claim, is:

- 10 1. A full-floating hydrometer comprising a plurality of indicator elements of different specific gravity and arranged in the order of their specific gravities and means for flexibly connecting said indicator elements together, said hydrometer being adapted for operation at all times independently of the vessel containing the liquid to be measured.
- 20 2. A hydrometer comprising a plurality of indicator elements of different specific gravity and arranged in the order of their specific gravities and means for flexibly connecting said indicator elements together, said indicator elements bearing indicia whereby to indicate by their position the density of the liquid in which the hydrometer is placed.
- 30 3. A hydrometer comprising a plurality of indicator elements bearing indicia, means for flexibly connecting said elements together, each succeeding element being of such constituency that, when floating and all of the preceding elements submerged, these submerged elements will cooperate together with the next succeeding floating elements to control the indication of the density of a liquid in which the hydrometer is placed.
- 40 4. A hydrometer comprising a plurality of indicator elements registering different specific gravities, and a flexible member to which all of said elements are connected, each succeeding element indicating a lower specific gravity, being of such constituency that when floating in a liquid, and all the preceding elements submerged, the submerged elements will cooperate together with the next succeeding floating element to control the indication of the specific gravity of the liquid.
- 50 5. A hydrometer including a plurality of indicating elements of different specific gravities, and means for interconnecting said elements, so that the weight of the elements as they successively sink in a liquid will be accumulative in effect upon the element which floats and is next in order to the

last element which sinks whereby to indicate the density of the liquid.

6. A hydrometer comprising a plurality of indicating elements of different specific gravity and a flexible connecting member, said indicating elements being arranged at equal intervals on said flexible connecting member and in the order of their specific gravity. 60

7. A full-floating hydrometer comprising a plurality of indicator elements of different specific gravities, and means for flexibly connecting said elements together, said indicator elements and connecting means being adapted for operation at all times independently of the vessel containing the liquid to be measured. 70

8. A flexible hydrometer adapted to float upon the surface of a liquid comprising a plurality of indicator elements, one of said indicator elements being of a density at least as great as that of the liquid, the remaining elements being of such buoyancy as to indicate, by the number of submerged elements, 80 the specific gravity of the liquid, and means for flexibly securing said indicator elements together. 75

9. A flexible hydrometer adapted to float upon the surface of a liquid comprising a plurality of indicator elements, one of said indicator elements being of a density at least as great as that of the liquid, the remaining elements being of successively increasing buoyancy so as to indicate by a successive increase in the number of submerged elements successive decrements in the specific gravity of the liquid, and means for flexibly securing said indicator elements together. 90

10. A hydrometer adapted to float in a liquid, comprising a plurality of indicator elements, one of said indicator elements having a density at least as great as that of the liquid, means for flexibly connecting said indicator elements together whereby to render their action mutually dependent, said hydrometer being adapted for operation at all times independently of the vessel containing the liquid to be measured. 100

In testimony whereof I affix my signature in presence of two witnesses.

THOMAS MIDGLEY, JR.
